CLAIM

The ornamental design for a concrete form splash funnel, as shown and described.

DESCRIPTION

FIG. 1 is a side elevational view of said concrete form splash funnel with the understanding that the other side elevational view is the same;

FIG. 2 is an end elevational view of the concrete form splash funnel with the understanding that the other end elevational view is the same;

FIG. 3 is a top plan view of said concrete form splash funnel; and,

FIG. 4 is a bottom plan view of said concrete form splash funnel.
